UNITED STATES PATENT OFFICE.

BICKNELL HALL, OF ABINGTON, MASSACHUSETTS, ASSIGNOR TO HALL CO., OF BOSTON, MASSACHUSETTS, A CORPORATION OF MASSACHUSETTS.

VARIABLE-SPEED MECHANISM.

Application filed June 17, 1918. Serial No. 240,325.

To all whom it may concern:

Be it known that I, BICKNELL HALL, a citizen of the United States, and a resident of Abington, in the county of Plymouth and State of Massachusetts, have invented an Improvement in Variable-Speed Mechanism, of which the following description, in connection with the accompanying drawings, is a specification, like characters on 10 the drawings representing like parts.

This invention relates to variable speed mechanism, the object thereof being to improve, simplify and render the same more compact. The present application is a re-filing, with the same disclosure, of my application, Serial No. 204,100, a renewal of Serial No. 507,616, originally filed July 14, 1909.

The nature of my invention will best appear from a description of one embodiment thereof selected for illustrative purposes and shown in the accompanying drawings, wherein--

Fig. 1 is a side elevation with the casing in section of a speed varying mechanism embodying my invention;

Fig. 2 is a vertical, longitudinal, central section of the mechanism shown in Fig. 1;

Fig. 3 is a section taken at right angles 20 to that of Fig. 2;

Fig. 4 is an end elevation representing in full and dotted lines one form of means for changing the position of the adjustable disk bearings;

Fig. 5 is a vertical, transverse section taken through one of the adjustable disk bearings and the gear for adjusting the same;

Fig. 6 is a perspective view of the main or drive shaft;

Fig. 7 is a transverse section upon the line 7—7 of Fig. 1 and representing the relation of one set of gear segments to the adjacent fixed bearing when said fixed disk bearing an adjacent adjustable disk bearing and its transmission ring are concentrically arranged;

Fig. 8 is a similar view of said parts when said fixed disk bearing and adjustable disk bearing and its transmission ring are eccentrically arranged;

Figs. 9 and 10 are views similar to Figs. 7 and 8, but representing the relation of the second set of gear segments to the fixed disk bearing adjacent thereto;

Figs. 11 to 18 inclusive are diagrams representing the path of movement of one of the fixed disk bearings and its gear segments with respect to the internal fixed gear during a single cycle of said fixed disk bearing;

Figs. 19 to 26 inclusive are diagrams representing the path of movement of the other fixed disk bearing and its gear segments during the corresponding cycle of said other fixed disk bearing;

Figs. 27, 29 and 31 are diagrams representing corresponding phases of one of the fixed disk bearings and its gear segments in different positions of adjustment of the 70 adjacent adjustable disk bearing;

Figs. 28, 30 and 32 are diagrams of corresponding phases of the other fixed disk bearing and its gear segments in the same several positions of adjustment of the corresponding adjustable disk bearing; and

Figs. 33 and 34 represent in side elevation and end view respectively, means for adjusting the position of the fixed internal gears.

Referring first to Figs. 1 to 6 inclusive, upon a suitable base (not shown) are erected two end standards 1, 2 herein shown as circumferentially grooved to receive a cylindrical casing 3 preferably entirely enclosing the mechanism excepting at the point from whence power is delivered. Within bearings in said standard is mounted a drive shaft 4 having keyed thereon a pulley 5, to which power may be applied from any suitable source, whereby the shaft may be driven at a constant speed in one direction. As shown most clearly in Fig. 6, the drive shaft has formed with or fast thereon eccentric seats 6, 6', 7, 7'. While my invention 90 may be embodied in a construction having a single fixed disk bearing, a single adjustable disk bearing and related parts to be hereinafter described, preferably I employ a plurality and in the present embodiment of the invention a pair of each of said parts. Inasmuch as in this embodiment of the invention various parts are duplicated, it will be necessary to describe in detail but one set of parts, excepting in so far 100 as it is essential to make clear the different circumferential positions of certain of the members of said sets of parts.

The eccentric seat 6 is rectangular and square while the eccentric seat 7 is rectangular 110

lar but oblong. Seated upon the eccentric seat 6 is an eccentric disk 8. If desired the disk 8 may be integrally formed with the seat 6. Upon the inner face of the disk 8 is an annular flange 9 or other suitable formation. Upon the oblong seat 7 is positioned a slotted disk bearing 10, the diametral slot 11 thereof being of such length as to permit the shifting of the disk bearing 10, so as to 10 vary its eccentricity with reference to the drive shaft 4. While any suitable means may be employed to vary the eccentricity thereof, preferably I form with or attach to one of the walls of the slot 11 a rack 12 meshing with an elongated pinion 13 mounted within the drive shaft 4, which for that purpose is made hollow for a portion of its length, as represented in Fig. 3.

Inasmuch as the eccentricity of the disk 8 is unchangeable, I shall herein term the said part the fixed disk bearing, and as the eccentricity of the slotted bearing 10 may be varied or eliminated, I shall term the same the adjustable disk bearing.

Surrounding the fixed bearing 8 and fixedly attached to the inner face of the standard 1 by bolts 14 or otherwise is an internal gear or annular rack 15.

Upon the annular flange 9 of the fixed disk bearing 8, I mount one or more herein toothed gear segments, shown most clearly in Figs. 7 and 8, and therein lettered *a*, *b*, *c* and *d*, four being preferably employed. The said gear segments are of any suitable circumferential extent and are loose upon said flange so as to be moved or slid circumferentially thereon and angularly with respect to the drive shaft when the eccentricity of the adjacent adjustable disk bearing is altered. Each of said gear segments is provided with an angular spoke or lug 16, the foot 17 whereof serves as the point of pivotal attachment thereof to its segment. The upright portion of each spoke or lug may 45 therefore be shifted from time to time as hereinafter described in varying the eccentricity of the adjacent adjustable eccentric bearing.

Loose upon the adjustable eccentric bearing 10 is a transmission ring 18, herein represented as made in two parts for convenience in assembling. Each part of said ring is provided with an annular seat 19, thus affording a flange 20, the two flanges overlapping the adjustable disk bearing 10 as represented and confining the ring thereon. The two parts of the said transmission ring are suitably secured together as by means of screws 21. That portion of the transmission ring 18 that is positioned next the gear segments *a*, *b*, *c* and *d* is provided upon its face adjacent said gears with a suitable number of radial grooves, which in this embodiment of my invention are four in number and are positioned at right angles to each other, the

end of certain of said grooves being shown at 22, in Fig. 1, and the other grooves being formed with relation thereto as indicated. Within each of said grooves is arranged the upright portion of the spoke or lug of one of the gear segments. In Fig. 2, two of the spokes or lugs of said gear segments are represented as positioned within the corresponding diametrically arranged grooves.

The drive shaft 4, as shown in Figs. 2, 3 and 6, is provided with a hub 23 loose whereon is a gear 24, herein termed a driven element and from which power may be conveyed in any suitable manner, as by means of a gear 25 meshing therewith. It is apparent, however, that the driven element, of any selected character, may be arranged in any proper manner to take power from the transmission ring or rings, which themselves are driven elements; and also serve to connect said segments with the adjustable eccentric disk 8. Thus through their spokes or lugs the segments are operatively associated with a driven element, namely, the ring 18 and also through said spokes or lugs and through said ring 18 are operatively associated with the adjustable eccentric. As represented most clearly in Fig. 2, that face of the gear 24 that is adjacent the right hand transmission ring 18, viewing Fig. 2, is provided with a diametral groove 26, and in the adjacent face of the transmission ring 18 is a similar diametral groove 27 (see Fig. 1) arranged perpendicular to the groove 26. Positioned between the driven gear 24 and the transmission ring 18 is a so-called unison ring 28 having opposite lugs 29 received within the diametral groove 26 and intermediate lugs 30 received within the diametral groove 27, whereby circumferential movement is conveyed from the transmission ring 18 to the driven gear. Instead of the unison ring or rings, I may employ any means for conveying movement from the transmission ring to the ultimately driven element, provided such means conveys movement uniformly, that is, provided such means does not vary or alter in transmission the speed of movement imparted to it by the transmission ring, which imparted speed or movement varies with each adjustment of the adjustable disk bearing.

I have thus far described the preferred construction of parts involving one set of elements, or that shown in Fig. 2 at the right of the driven gear 24. The construction of parts making up the second set of elements or that shown in Fig. 2 at the left of the driven gear 24, when a second set of elements is employed, may be and preferably is substantially identical with that already described. In Figs. 9 and 10, I have represented the gear segments *a*', *b*', *c*' and *d*' of the second, or left hand set of elements viewing Fig. 2, and it will be noted that in the

position of parts represented in Figs. 7 and 9 the gear segments a' , b' , c' and d' are arranged respectively at an angle of 45° to the segmental gears a , b , c and d . Moreover the 5 diametral groove in the opposite or left hand face of the driven gear 24 is perpendicular to that shown in the right hand side and consequently the diametral groove in the adjacent face of the left hand transmission 10 ring is normal to that in the right hand transmission ring. The grooves 22 in the outer face of the left hand transmission ring for the reception of the spokes or lugs of the gear segments a' , b' , c' and d' are 15 respectively at an angle of 45° to the similar grooves 22 in the face of the right hand transmission ring 18, as indicated in Fig. 1. It will be understood that the number of 20 grooves in the several parts and their angular arrangement will be varied in different embodiments of my invention, in accordance with the number of gear segments employed.

Having reference first to Fig. 7, it will be apparent that when the shaft 4 is rotated 25 clockwise the fixed disk bearing 8 will gyrate about said shaft in the manner of an eccentric with the gear segments thereof consecutively meshing with the internal fixed gear or annular rack 15. The said 30 fixed disk bearing 8 rolls about the inner face of the internal fixed gear or rack 15 with the said gear segments in mesh with the latter, and were the said fixed disk bearing provided with an uninterrupted gear 35 the teeth thereof would constantly mesh with those of the said internal gear or rack. Inasmuch, however, as the gear segments are 40 preferably spaced substantially as shown, and as neither set of said segments in itself makes a complete gear, it is apparent that the said gear segments intermittently and 45 consecutively engage the said internal gear or rack. Inasmuch as the shaft 4 is rotated clockwise, as indicated by the arrow in Fig. 50 7, each gear segment a , b , c or d , as it engages with the internal gear or rack 15 will be driven counterclockwise as indicated by the arrow adjacent the gear segment a in Fig. 7. This movement of the gear segment a counterclockwise is imparted by the 55 spoke or lug of said gear to the transmission ring 18, and thence through the unison ring 28 or other suitable connections to the drive gear 24 or other driven element, thereby driving the same in a direction opposite to that of the direction of movement of the driven shaft 4. It is, of course, evident that the drive shaft 4 may be rotated in either direction, the driven gear 24 being thereby 60 rotated in an opposite direction, in that relation of the parts thus far described.

Viewing Figs. 7 and 9, it will be noted that in this embodiment of the invention the gear segments a , b , c and d and a' , b' , c' and d' 65 are complementally arranged with respect

to each other, so that the two sets of gear segments together constitute substantially a complete gear.

As previously stated, the disk 8 is of a fixed or unvarying eccentricity. The eccentricity of the disk 10 may be rendered that of the disk 8, or it may be made different therefrom to any extent within the limits imposed by the capacity for adjustment of the disk 10, being made greater or less than the same as desired. Within the scope of my invention the disk 10 may be adjusted to any desired extent, thus varying its eccentricity to any desired degree. If the adjustable disk 10 be so positioned upon its seat that it is of the same eccentricity as the fixed disk 8, then the transmission ring 18 is of the same eccentricity as said fixed disk 8, and upon rotation of the drive shaft 4 in either direction the fixed disk 8 rolls about within the internal gear or annular rack 15 with the gear segments thereof meshing therewith, but with the consequent reverse rotation of the said gear segments and consequently with the reverse rotation of the driven gear 24 at a speed which is the same as that at which the gear 24 would be driven were the said eight segments a , b , c , d and a' , b' , c' , d' assembled in fixed relation to constitute a single complete gear rolling about and meshing with the internal gear or rack 15. If the eccentricity of the disk 10 exceeds that of the disk 8, then the speed of the gear 24 is increased over that just referred to and if it be less than that of the disk 8, then the speed of the gear 24 is less than that above indicated.

In Fig. 7, the center of rotation of the shaft 4 is indicated at A, while the centers of the fixed disk bearing and the adjustable disk bearing and its transmission ring are represented at B. The several gear segments a , b , c , and d are so related to each other that axial lines drawn through them and their spokes 16 intersect at the centers of said fixed disk bearing 8 and the adjustable disk bearing 10, with the previously stated result of driving the gear 24 at a speed equalling that obtained by rolling a gear composed of said eight segments in fixed relation within and meshing with the fixed gear 15. Preferably the parts are brought into this relation as a preliminary to obtaining the desired speed. Such eccentricity may be varied by moving the slotted disk bearing 10, viewing Fig. 7, upward to obtain a still greater speed of the gear 24 or downward, viewing said Fig. 7, and hence toward the position shown in Fig. 8, this downward movement being of any desired extent within the capacity of the mechanism, to obtain the desired diminution of speed of the driven gear 24.

When the centers of the fixed disk bearing and the adjustable disk bearing are the

same, there is as described gyratory movement of said parts, resulting in the reverse driving of said segments and consequently of the gear 24.

As, however, the eccentricity of the adjustable disk bearing 10 is made different from that of the fixed disk bearing 8 by moving the former toward the center of the shaft 4 or toward the point A in Fig. 7, the result is to enforce a new position of the transmission ring 18, the unison ring adapting itself to any position of adjustment. The adjustment of the disk bearing 10 and consequently of the transmission ring 18 compels a repositioning of the gear segments *a*, *b*, *c* and *d* upon the annular flange 8, as indicated for example in Fig. 8, where, however, the adjustment is carried so far as to compel the rotation of the gear 24 in the same direction as the shaft 4, as will be more fully explained. This repositioning of the gear segments is due to the fact that the downward movement of the transmission ring 18 enforces the downward movement of those spokes or lugs 16 of the gear segments that do not occupy a vertical position. Viewing Fig. 8, it will be apparent that the lugs or spokes of the gear segments *b*, *d* have been moved bodily downward carrying with them said gear segment *b*, *d*, but that said lugs or spokes are still horizontally arranged and that an axial line drawn therethrough intersects in the shaft 4, as in Fig. 8, an axial line drawn through the lugs or spokes of the gear segments *a*, *c*.

The positioning of the adjustable disk bearing 10 so as to make its eccentricity different from that of the fixed disk bearing 8 institutes a secondary or neutralizing gyration of said adjustable disk bearing 10 which neutralizes to a greater or less extent that of the still continuing primary gyration of the fixed disk bearing 8, the extent of the neutralization being dependent upon the extent of the change in position of the adjustable disk bearing 10, the result being the rotation of the driven gear 24 still in the reverse direction to that of the drive shaft 4 but at a different speed with respect to that obtained when the eccentric disks 8 and 10 are of the same eccentricity. The nearer the adjustable disk bearing 10 is moved toward concentricity with the center of rotation A of the driving shaft 4,—that is, the less its own gyration,—the greater will be the neutralizing effect of the said secondary gyration,—that is, of the adjustable disk bearing,—and hence the less will be the resultant rate of rotation of the driven gear 24, but still in a direction the reverse of that of the shaft 4, or, in other words, the less will be the rate of rotation of the transmission ring 18. The greater the differential between the primary and secondary gyrations, the greater the difference in speed of the driven gear 24 with respect to the drive shaft 4. If the disk bearing 10 be moved until it is in concentricity with the center of rotation of the driving shaft 4, then the gyration of the disk bearing 10 wholly ceases and therefore said disk wholly neutralizes that of the main or primary gyration of the fixed disk bearing 8, because of the now existing differential between the movements of the fixed and adjustable disk bearings, thereby causing the main drive shaft 4 to rotate without any driving effect upon the gear 24. If this adjustment of the bearing disk 10 be continued in the same direction until the transmission ring be shifted so that its center is at the other side of the axial center of the driving shaft 4 (that is, below the said axis of the said shaft when viewing the drawings) then there is instituted a secondary gyration which is not a neutralization of but is supplemental to the main or primary gyration of the fixed disk bearing 8, with the result that the gear 24 is now driven in the same direction as the driving shaft 4 but at a speed dependent upon the amount of such secondary but now supplementary gyration. The speed of rotation of the gear 24 in the same direction as the driving shaft 4 is dependent merely upon the extent of adjustment of the disk bearing 10 or in other words the extent of adjustment of the center of the transmission ring below that of the shaft 4, viewing the drawings, and in the various embodiments of my invention may be made as great as desired. Thus my invention contemplates the reverse driving of the gear 24 at any speed and the forward driving of said gear at any speed, with adjustment of the parts to effect any intermediate speed of said gear 24 in either direction.

In Fig. 7, I have illustrated the position of the gear segments *a*, *b*, *c* and *d* at one position of adjustment of the bearing disk 10, the gear segment *a* being then in mesh with the fixed internal gear or annular rack 15, with the resultant movement of said gear segment *a* contraclockwise. The continued rotation of the drive shaft 4 clockwise rolls the said fixed disk bearing 8 about within said internal gear or annular rack and during such movement of the shaft the gear segments *a*, *b*, *c* and *d* come successively into mesh with said internal gear 15, thereby compelling continued rotation of said gear 24.

Comparing diagrams 11 to 18 inclusive with diagrams 19 to 26 inclusive, it will be apparent that upon the described rotation of the shaft 4 in a clockwise direction, as the gear segment *a* moves from its position of engagement with the internal gear 15 as illustrated in Fig. 7, the gear segment *a'* is brought into mesh therewith, and that as it in turn is withdrawn from such engagement the gear segment *b* is brought into engage-

- ment, this action being continued with the segments b' , c , c' , d , d' in the order named. The result is an engagement with the internal gear 15 of one or more of all the gear segments at all times, the gear segments being of such extent that before one segment is withdrawn from such engagement another is brought thereinto. The employment of gear segments permits the true rolling action of successive gear segments into and out of engagement with the fixed internal gears 15.
- Comparing Figs. 8 and 10, it will be evident that whatever be the adjusted eccentricity of the bearing disk 10, the resultant positions of the gear segments a , b , c , d , and a' , b' , c' , d' are such that one of said gear segments is constantly in mesh with the internal gear 15, thereby compelling a constant rotation of the driven gear 24. After a gear segment is withdrawn from engagement with the internal gear 15, its subsequent position upon the flange 9 is immaterial until it is again brought into mesh with said internal gear. It matters not that in certain positions of adjustment a gear segment of each set is in mesh with the internal gear 15, nor that in certain positions of adjustment the gear segments of one set or the other be spaced a greater distance apart than in other positions of adjustment, for whatever be the position of adjustment, the gap between adjacent gear segments of one set is always bridged by a gear segment of the opposite set, thereby compelling continuous rotation of said driven gear 24.
- In Fig. 11, the center of rotation of the fixed disk bearing 8 is indicated at X , and the center of rotation of the adjustable disk bearing 10, and the transmission ring is indicated at Y , while the center of rotation of the driving shaft 4 is indicated at Z . The circle X' passing through the center of rotation X of the fixed disk bearing indicates the circular path of travel of the said fixed disk bearing, while the circle Y' passing through the point Y indicates the circular path of travel of the adjustable disk bearing. The corresponding points X , Y and corresponding circles X' , Y' in Figs. 11 to 18 inclusive and Figs. 19 to 26 inclusive represent the centers of rotation and paths of travel of the fixed disk bearing and adjustable disk bearing through one cycle of their movement. As the circle Y decreases in radius, owing to the further adjustment of the disk bearing 10, the rate of rotation of the driven gear 24 becomes less and less and finally when the circle Y , or path of travel thereby indicated, vanishes or merges into the center of rotation Z , of the drive shaft 4, the rotation of the driven gear 24 in a direction contrary to that of the shaft 4 is wholly neutralized so that said gear becomes stationary. This position of the parts is indicated in the diagrams shown in Figs. 29 and 30.
- As indicated in Figs. 31 and 32, the adjustment of the eccentric bearing 10 has been continued until its center of rotation Y'' is below that of the center of rotation Z of the driving shaft 4 with the result that, as previously stated, the gyration of the transmission ring is now supplemental to that of the main gyration, or gyration of the fixed disk bearing 8, and therefore compels a forward rotation of the driven gear 24, or, in other words, a rotation thereof in the same direction as the driving shaft 4.
- From the foregoing description, it will be understood that the gear segments always travel in the same gyratory path with relation to the fixed disk bearings 8, inasmuch as they are carried by the circumferential flanges 9 of the fixed eccentric disk bearings 8. During such gyratory movement, they roll around within and in mesh with the fixed internal gears 15. The speed of the shaft and eccentrics is always the same, and when the adjustable eccentrics 10 are of the same eccentricity as the fixed eccentrics 8, then, as previously stated, the resulting speed of the driven gear 24 equals that derived from complete gears rolling within and in mesh with the said internal gears. By altering the eccentricity of the said adjustable disk bearings 10, however, the circular path of movement of the centers of the said disks 10 is increased or decreased in diameter according as the eccentricity of said disks is increased or diminished. If the circular path of movement of the centers of the eccentrics 10 equals that of the centers of the eccentrics 8, as stated, the resulting speed is that of complete gears rolling in mesh with the fixed internal gears 15, but if the circular path of the centers of the eccentrics 10 exceeds that of the centers of the eccentrics 8, the resulting speed is greater, and if the disks 10 be brought into concentricity with the shaft 4, the circular path of movement of the centers of said disks 10 is reduced to a point or disappears with the result that no driving movement is imparted by the said disks 10 to the gear 24.
- The pinion or pinions 13 may be rotated in any suitable manner to adjust the eccentric disk bearings 10. Herein as shown in Fig. 3, a single elongated pinion 13 is employed to adjust both disk bearings 10. In order to rotate the pinion 13, I have, in Figs. 1, 2, 3 and 4, represented a handle 31 provided upon a disk 32 having a hub 33 mounted in a standard 34 having therein a segmental slot 35, with which engages a bolt or set screw 36 permitting any desired adjustment of said disk 32 and handle 31. Herein shown as having a tongue and groove guiding engagement with the disk 32 is a

casing or frame 37 keyed to the shaft 4 and having an internal gear or annular rack 38.

Keyed upon the spindle of the adjusting pinion 13 is a pinion 43 to which I impart 5 one revolution for each revolution of the internal gear 38, in order that the relative circumferential positions of said pinion and gear may remain unaltered during the rotation of the drive shaft 4, until it is desired 10 to re-adjust the position of the eccentric disk bearings 10. Any suitable gearing may be employed for the purpose. Herein I have shown a gear 39 keyed upon a spindle 39' mounted upon a bracket 40 extending from 15 the disk 32.

Said gear 39 is one half the diameter of the internal gear 38 and meshes therewith. Formed with or fast upon the spindle 39' is a pinion 41 meshing with a pinion 42 loose 20 upon a stud extending from the disk 32, and meshing with said pinion 43, of which it is one half the diameter. Upon circumferential adjustment of the disk 32 by movement of the handle 31 the gear 39 is rolled 25 within and upon the internal gear 38 and through the described train of gearing imparts rotative movement to the pinion 43, and hence to the elongated pinion 13, relative to the driving shaft 4, thereby altering 30 the adjustment of the eccentric disk bearings 10 to the extent desired.

I have heretofore referred to the internal gear or gears 15 as fixed. By this term I do not intend to preclude their capacity for 35 adjustment. It may be desirable circumferentially to adjust said internal gears, as for instance to avoid the necessity of forming said gears with special teeth. In other words, at the commencement of the operation 40 when one of the segmental gears is about to engage with its internal gear, in which case the parts may be positioned substantially as shown in Fig. 11, it would be necessary in this embodiment of my invention 45 to provide the internal gears with a special form of teeth, unless it were possible circumferentially to adjust said internal gears to permit the proper meshing of the teeth of the gears 15 and the first gear segments. 50

Any suitable means may be employed circumferentially to adjust said internal gears. In Figs. 33 and 34, I have shown means for effecting this result, it being understood that 55 by the same or similar means both internal gears shown in this embodiment of my invention may thus be adjusted. This desirability of circumferential adjustment particularly arises in the case of the use of a 60 plurality of fixed internal gears, such as 15.

Referring for purposes of description merely, to that internal gear shown at the left in Fig. 3, said gear instead of being secured fixedly in position is provided externally as shown in Fig. 34 with a suitable

number of teeth 44, with which meshes a worm 45 upon a shaft 46 provided at its upper end with a hand wheel 47. Said shaft is mounted in suitable bearings in brackets 48-48 extending from the standard 2. 70 Preferably I provide means simultaneously to adjust the internal gear or gears 15 and the elongated pinion 13 controlling the position of the adjustable segments 10 to maintain the proper relation of the parts. To 75 this end, I may omit the handle 31 from the disk 32 shown in Fig. 4, and in lieu thereof provide the shaft 46 with a beveled pinion 49 meshing with a beveled gear 50 fast upon a shaft 51 mounted in a bearing 80 in the standard 2 and provided upon its opposite end with a pinion 52 meshing with a gear 53 formed upon the periphery of the disk 32. It is apparent that by turning the hand wheel 47 the internal gear 15 may be 85 rotated to the desired extent to adjust the same with respect to the segmental gears and that simultaneously the position of the adjustable segments 10 may be altered, thereby to produce the desired speed of the driven 90 gear 24. In the embodiment of my invention herein described and wherein two internal gears 15 are employed, I provide suitable mechanism circumferentially to adjust both of said gears. If desired, such mechanism may be connected for simultaneous operation so that but a single hand wheel 47 95 or the like is necessary.

In the device illustrated herein the driving belt is applied to the driving pulley 5, which, 100 with its shaft 4, eccentric bearings 8 and 10, and cooperating internal gear 15, transmit rotary motion to and through the other parts of the device, hence said driving pulley, its shaft, and the eccentric bearings may together be considered as the driving element, or any one of them might be so considered, upon the understanding that the effective axis of said driving element is that which transmits motion to the gear segments. 105 Said effective axis is a resultant of the fixed eccentricity of the bearing 8 and the adjustable eccentricity of the bearing 10 as heretofore described, and is adjustable as to its path of movement according to the adjustment of said eccentric bearing 10. In other words, the effective axis of the driving member or group of members constituting what I have herein referred to as the driving 110 element of the device, is the gyrating axis about which are grouped the pivot pins 17 of the gear segments $a-d$ and $a'-d'$, a resultant of the relative adjustment of the axes of the eccentric bearings 8 and 10, which latter are upon, moved with, and together determine 115 the effective axis of the driving element of the device.

In the device illustrated, power is taken from the transmission rings or straps 18 through the unison rings 28 and the gear 130

24, and said members together or separately may be considered the driven element of the device; the axes of said driven rings 18 and of the driving element heretofore mentioned are relatively adjustable into positions of greater or less relative eccentricity.

Operatively interposed between the driving and driven elements are the groups of 10 segmentally shaped members or toothed gear segments, $a-d$ and $a'-d'$ which serve to transmit motion and power from the driving element to the driven element. Each such toothed gear segment together with its spoke 15 or lug 16 and pivot pin 17 may conveniently be termed a driving unit for transmitting motion from the driving to the driven elements. The driving units of each group are distributed in a single plane about the axes 20 of the driving and driven elements and are operatively connected with one of said elements, herein the driving element, in a crank-like manner, that is to say, the driving units are moved by the drive shaft and eccentricities and the connections therewith in the manner of a crank which furnishes the connection between said driving element and the driving unit or units.

In any adjusted position of the adjustable eccentric bearings 10, whether of greater or less or the same eccentricity as the fixed eccentric bearings, the outer end of each driving unit where the teeth of a segment engage the internal teeth of the gear 15, 30 makes intermittent engagement with said gear and the points of such intermittent engagement change or are adjustable around the pitch line circle or circumference thereof since at each succeeding engagement said segment engages a new tooth or teeth more or less removed from that or those previously engaged, the points of engagement progressing around the said gear 15 in steps determined as to the period, spacing, or rapidity 40 of engagement according to the extent of the relative eccentricity above mentioned.

In engaging and disengaging from said gear 15 each driving unit approaches and 50 recedes from said member in a rolling manner, that is to say, the action is such that the two members, so to speak, roll together and away from each other; not only is the action of meeting and receding thereby made easy and susceptible of ready and effective guiding, but the period of effective normal driving contact or engagement between the same may thereby be prolonged. Such engagement and disengagement of the 55 effective driving parts relieves the same of unnecessary frictional engagement between successive points of intermittent engagement and renders also the adjustment of the transmission from one to another speed 60 more easy, mechanical and efficient. Thus, while the engagement is intermittent, it

varies in duration according to the extent of said relative eccentricity above mentioned and according to the variation of transmission obtained thereby or therefrom.

An important characteristic of the transmission device described is that the driving action or thrust of the driving unit to and upon the engaged element is in a line normal to the abutment or thrust-receiving face on said element with which it is engaged 70 during the driving period; in the present instance that abutment face is the effective face of the internal tooth or teeth on the annular member or gear 15 with which the driving unit, for the time being, is engaged. 75 An arrangement that permits the driving thrust to be delivered upon the abutment face of the engaged element in a line normal or substantially normal to said face, renders the device positive in its action and 80 free from heat generating conditions that characterize an ordinary clutch or gripping arrangement for delivering a driving thrust from the driving unit to the member engaged thereby. 85

If the driving thrust were exerted in a direction not normal to the abutment face of the element engaged by it, the moment the angle of repose at either side a line truly normal to that abutting face be passed, the 90 driving thrust would tend to produce a lateral slipping action between the driving unit and said face, which would require resistance by some friction clutch or other device. So long, however, as the driving thrust is within the angles of repose at the 95 sides of a line truly normal to the abutment face, said line of thrust may be said to be substantially normal to said face and may be employed as freely as if it were a 100 true normal to deliver positive driving force from one part to its engaged part without liability to lateral slip and without requiring any supplementary clutches or other devices to maintain the engagement. 105

Where the driving units and engaged elements are provided with gear teeth, as in the present instance, the range of adjustment in speed due to the relative adjustment of the effective axes of the driving and driven elements would be limited to a step adjustment and to a maximum number of steps between speed ranges dependent upon the size and number of teeth, were it not that in the present instance the adjustment is rendered 115 truly universal so that any intermediate speed may be obtained from minimum to the maximum in either direction due to the adjustability of the internal gear or gears 15 upon their own axes, as by the means shown in Figs. 33 and 34. By so adjusting said gears circumferentially and relatively to the segments the proper engagement therebetween is assured in any adjusted position of the eccentric bearings. Thus the intermit- 120 125 130

tent rolling engagement of said segments and gear is made universally adjustable circumferentially about the axis of said engaged gear or member throughout a complete circle.

Each of the segments or driving units in its movement toward and from its engaged element moves in an endless path until the limit of movement is reached, where it moves directly radially in a straight line as stated, and whatever its movement, whether in a straight line or in an endless path, the driving units at their effective driving portions approach and recede from the engaged element in a general direction that is substantially normal to that element in the region of that engagement.

As already observed, the points of engagement of the driving units with the engaged element shift variably around the latter according to the path of movement of the effective axis of the driving element, and according to the extent of relative eccentricity of the axes of the driving element and the driven rings 18; as the said relative eccentricity is varied, the radial position of a driving unit with respect to the axis of the driven element when such unit is driving is also varied, as well as the speed transmitted.

The driving units and gear 15 whether actually engaged or for the time being disengaged, are always in juxtaposition where they may be readily guided into the next engagement by suitable means as here provided. In the present instance it will be observed that during the periods of actual disengagement between the teeth of the segments and the element that is engaged thereby said segments are positively held or guided by the annular flange 9.

Having thus described one illustrative embodiment of my invention, I desire it to be understood that although specific terms are employed, they are used in a generic and descriptive sense and not for purposes of limitation, the scope of the invention being set forth in the following claims.

Claims.

1. Speed varying mechanism comprising in combination driving and driven elements, the former including a drive shaft, a series of toothed gear segments distributed about said shaft, gyratorially acting means upon said shaft and supporting said segments for angular movement about said shaft, said means being effective to vary the radial position of one or more of said segments with respect to said drive shaft, a toothed gear surrounding the shaft and with which said segments are adapted to mesh, and driving connections between said segments and said driven element.

2. Speed varying mechanism comprising in combination driving and driven elements,

the former including a drive shaft, transmission members thereon of fixed and adjustable eccentricity respectively, a circumferential series of toothed gear segments movably carried by one of said members

70

and operatively associated with the driven element and with the other of said members, means to position said adjustable transmission member in concentric or eccentric relation to said fixed transmission member, and a surrounding toothed gear with which said segments are adapted to mesh.

75

3. Speed varying mechanism comprising in combination driving and driven elements, the former including a drive shaft, a pair of transmission members supported thereon and of fixed and variable eccentricity respectively, one or more toothed gear segments slidably supported by one and operatively connected to the other of said transmission members, and to said driven element, and a surrounding toothed gear with which said segment or segments are adapted intermittently to engage.

80

4. Speed varying mechanism comprising in combination driving and driven elements, the former including a drive shaft, a gyratory member of fixed eccentricity upon said shaft, toothed gear segments supported by said member and circumferentially movable relatively thereto, a toothed gear with which said segments are adapted intermittently to engage, means variably to position said segments about said gyratory member, and connections between said segments and said driven element.

90

5. Speed varying mechanism comprising in combination driving and driven elements, the former including a drive shaft, fixed and adjustable gyratory transmission members carried thereby, toothed gear segments carried by one of said transmission members and circumferentially movable relatively thereto, a normally stationary toothed gear with which said segments circumferentially engage and operating connections between each segment and said driven element including a ring loose upon the other of said transmission members.

100

6. Speed varying mechanism comprising in combination a drive shaft, driving and driven elements respectively fast and loose thereon, fixed and adjustable gyratory transmission members carried by said shaft, one or more toothed gear segments carried by one of said transmission members for circumferential movement relatively thereto, means upon the other transmission member variably to position said segment or segments, a toothed gear to be engaged by said segment or segments thereby to move the latter relatively to the transmission member carrying them, and positive connections between said segment or segments and said driven element.

115

110

115

120

125

130

7. Speed varying mechanism comprising in combination driving and driven elements, the former including a drive shaft, a gyroscopic member thereon, a plurality of circumferentially movable toothed gear segments carried by said gyroscopic member, means to vary the circumferential relation of one or more of said segments and said gyroscopic member, a toothed gear with which 5 said segments are adapted to mesh thereby to cause them to rotate relatively to said gyroscopic member while gyrating, and positive connections between said segments and the said driven element.
8. Speed varying mechanism comprising in combination driving and driven elements, the former including a drive shaft, a gyroscopic member thereon, a circumferentially movable toothed gear segment carried by 10 said gyroscopic member, means to vary the circumferential relation of said segment and said gyroscopic member, a toothed gear with which said segment is adapted to mesh thereby to cause it to rotate relatively to said gyroscopic member while gyrating, and driving connections between said segment and said driven element.
9. Speed varying mechanism comprising in combination driving and driven elements, the former including a drive shaft, a gyroscopic member thereon, a toothed gear segment carried by said member and angularly movable relatively thereto, means to vary the path of movement of said segment, a toothed gear with which said segment is 15 adapted to engage thereby to move the latter relatively to said gyroscopic member, and connections including a unison ring between said segment and said driven element.
10. In speed transmission mechanism for converting constant rotary to variable speed rotary motion, the combination of a drive shaft, fixed and adjustable gyroscopic transmission members thereon, toothed gear segments supported for angular sliding movement about one of said members, and operatively connected with and to be moved by the other of said members.
11. Speed varying mechanism comprising in combination a driving element including a drive shaft, fixed and adjustable gyroscopic transmission members thereon, a toothed gear surrounding said shaft, toothed gear segments supported for sliding movement circumferentially of one of said transmission members and operatively associated with the other of said members, said segments being adapted intermittently to engage said gear, and a driven element rotatably supported 50 about said shaft, there being positive connections between said segments and said driven element.
12. Speed varying mechanism comprising in combination a drive shaft, fixed and adjustable gyroscopic transmission members fast 55
- thereon, a toothed gear surrounding said shaft, toothed segments circumferentially movable upon one of said transmission members, having operating connections with the other of said transmission members, and adapted to mesh with said gear, a driven element loose upon said shaft, and connecting means including said operating connections and a unison ring surrounding said shaft between said segments and said driven element. 70
13. Speed varying mechanism comprising in combination driving and driven elements, the former including a drive shaft, a gyroscopic element fast thereon, one or more toothed gear segments carried by said gyroscopic element and operatively connected with said driven element, a toothed gear with which said segment or segments engage thereby to cause them to rotate relatively to said gyroscopic member while gyrating, means to vary the path of movement of said segment or segments, and means to adjust said gear. 80
14. Speed varying mechanism comprising in combination driving and driven elements, the former including a drive shaft, fixed and adjustable gyroscopic members thereon, toothed gear segments carried by one of said transmission members and circumferentially movable relatively thereto, a normally stationary toothed gear with which said segments intermittently engage, operating connections between each segment and said driven element and between each segment and the other of said transmission members, and means circumferentially to adjust said gear. 90
15. Speed varying mechanism comprising in combination driving and driven elements, the former including a drive shaft, toothed gear segments supported by said drive shaft and angularly movable relatively thereto, a normally stationary toothed gear, means cooperating with said drive shaft to roll said segments within and in intermittent driving relation to said gear, and positive driving connections between said segments and said driven element. 100
16. In speed transmission mechanism for converting constant rotary to variable speed rotary motion, in combination a drive shaft, an eccentric transmission member mounted on said shaft and having a flange, and a plurality of gear segments mounted and circumferentially movable upon said flange and relatively to each other, and means to cause said movement of the segments. 110
17. Speed varying mechanism comprising in combination driving and driven elements, the former including a drive shaft, a surrounding toothed gear, an eccentric transmission member mounted on said shaft and having an annular gear-supporting formation, a plurality of relatively movable 115
- 120
- 125
- 130

toothed gear segments supported by and circumferentially movable with respect to said formation and engageable with said gear, and driving connections between said segment or segments and said driven element.

18. Speed varying mechanism comprising in combination operatively connected driving and driven elements, the former including a drive shaft, an eccentric transmission member thereon, a surrounding toothed gear, a plurality of circumferentially shiftable toothed gear segments upon said transmission member and engageable with said gear, gyratorially acting means to vary the radial position of said segments with respect to the axis of the driven element and driving connections between said segments and said driven element.

19. Speed varying mechanism comprising in combination driving and driven elements, the former including a drive shaft, a transmission member of fixed eccentricity thereon, a surrounding toothed gear, one or more toothed gear segments carried by said transmission member, angularly movable relatively thereto and intermittently engageable with said gear, said segment or segments being connected with said driven element, and means to vary the relative radial position of said segments and said driven element whereby said angular movement of said segments imparts rotation to said driven element at speeds dependent upon said relative radial position.

20. Speed varying mechanism comprising in combination driving and driven elements, the former including a drive shaft, gyratory members thereon, and of fixed and variable eccentricity respectively, a fixed internal gear and connections between said gyratory members and said internal gear and also between said members and the driven element.

21. Speed varying mechanism comprising in combination a drive shaft, a driven element, and positive gearing connections between said drive shaft and driven element, said gearing being adjustable to effect the driving of the driven element at a greater, or less or equal speed with respect to said drive shaft and in either direction, and also at any intermediate speed.

22. Speed varying mechanism comprising in combination a drive shaft, a driven element loosely supported thereon, gyratory members upon said shaft and of fixed and variable eccentricity respectively, and driving connections between said members and said driven element, said connections including a circumferential series of toothed gear segments slidably supported on one of said gyratory members and slidably by the other of said members, a toothed gear

with which said segments are engageable, and radially movable blocks between said segments and said driven element.

23. Speed varying mechanism comprising in combination driving and driven elements, the former including a drive shaft, a gyratory member thereon, and a coacting series of toothed gear segments angularly movable upon said gyratory member; a normally stationary toothed gear with which said segments are adapted for intermittent rolling engagement, positive driving connections between said segments and said driven element to impart rotation to said driven element, and means to vary relatively to the axis of said driven element the radial position of said segments when in engagement with said gear.

24. Speed varying mechanism comprising in combination driving and driven elements, the former including a drive shaft, a surrounding toothed gear, gyratory members on said shaft, an adjustable member to modify the action of one of said gyratory members, a circumferential series of toothed gear segments supported for angular movement upon the other of said gyratory members and adapted to mesh with said gear, a ring-like member loose upon said first mentioned gyratory member and positive driving connections between said segments and said ring-like member, and between the latter and said driven element.

25. Speed varying mechanism comprising in combination a drive shaft, driving and driven elements respectively fast and loose thereon, primary and secondary gyratory transmission members upon said shaft, means to modify the action of said secondary gyratory transmission member, a circumferential series of toothed gear segments angularly movable about the axis of said primary gyratory transmission member, a toothed gear with which said segments are adapted for intermittent rolling engagement, a ring-like member loose upon said secondary transmission member, and positive driving connections between said segments and said ring-like member and between the latter and said driven element.

26. Speed varying mechanism comprising in combination a drive shaft, a driven element, positive gearing connections between said drive shaft and driven element, said gearing being adjustable to effect the driving of the driven element at a greater or less or equal speed with respect to said drive shaft and also at any intermediate speed.

In testimony whereof, I have signed my name to this specification.

BICKNELL HALL.
